UNITED STATES PATENT OFFICE.

WILLIAM P. PONDELICEK, OF CHICAGO, ILLINOIS, ASSIGNOR OF ONE-HALF TO JERRY J. PONDELICEK, OF CHICAGO, ILLINOIS.

DESIGN FOR A TUMBLER-HOLDER.

56,565.

Specification for Design.

Patented Nov. 9, 1920.

Application filed May 21, 1920. Serial No. 383,294. Term of patent 3½ years.

To all whom it may concern:

Be it known that I, WILLIAM P. PONDELICEK, a citizen of the United States, and residing at Chicago, in the county of Cook and State of Illinois, have invented a new, original, and ornamental Design for Tumbler-Holders, of which the following is a specification, reference being had to the accompanying drawing, forming a part hereof.

Fig. 2 is a side elevation showing a tumbler in place.

Fig. 3 is a similar view of the other side.

What I claim is:—

The ornamental design for a tumbler holder as shown.

WILLIAM P. PONDELICEK.
